United States Patent Office

Des. 193,507
Patented Sept. 4, 1962

193,507

CHAIR

Chester S. Urban, 2832 Wilmot St., Philadelphia, Pa.

Filed July 24, 1961, Ser. No. 66,029

Term of patent 14 years

(Cl. D15—1)

Fig. 1.

Fig. 2.

Fig. 3.

The side not shown is the same as the side shown.

The dominant features of my design reside in those portions shown in full lines on the drawing.

I claim:

The ornamental design for a chair, substantially as shown and described.
